E. R. SMITH

ROUTE MARKER FOR ADDRESSING MACHINES

Filed July 28, 1922

FIG. 1

By Attorneys
~~Southgate & Southgate~~

UNITED STATES PATENT OFFICE.

EDWIN R. SMITH, OF FITCHBURG, MASSACHUSETTS, ASSIGNOR TO AUTO-MAILING MACHINERY COMPANY, A CORPORATION OF MASSACHUSETTS.

ROUTE MARKER FOR ADDRESSING MACHINES.

Application filed July 28, 1922. Serial No. 578,183.

To all whom it may concern:

Be it known that I, EDWIN R. SMITH, a citizen of the United States, residing at Fitchburg, in the county of Worcester and 5 State of Massachusetts, have invented a new and useful Route Marker for Addressing Machines, of which the following is a specification.

This invention relates particularly to machines for addressing newspapers, magazines or other periodicals. In the use of such machines, the stencils for each particular route or mailing station are grouped together and are fed through the machine in 15 succession. It is desirable to operate the addressing machine continuously without stopping the machine at the end of each so-called "route" and when thus continuously operated some provision is necessary 20 to enable the operator to quickly separate and assemble the different route packages.

It is the object of my invention to provide means for thus distinguishing the routes, preferably by placing a mark on the 25 last paper or magazine in each route.

A particular feature of my invention consists in controlling the operation of the route marker directly by the stencils. A further feature relates to the provision of 30 both primary and secondary contact closing devices, the circuit being broken at a point removed from the stencils, magazines and marking mechanism, and fully protected.

My invention further relates to arrangements and combinations of parts which will be hereinafter described and more particularly pointed out in the appended claims.

A preferred form of the invention is shown in the drawings in which—

40 Fig. 1 is a diagrammatic elevation, showing the relation of the different parts of my improved route marker;

Fig. 2 is a side elevation of the marking mechanism and certain parts associated 45 therewith;

Fig. 3 is a plan view of a series of stencils; and

Fig. 4 shows the mark as it appears on the magazines.

50 Referring to Fig. 1, I have shown conveying devices 10 and 11 by which magazines M are fed successively through the machine. The stencils S are also fed succes-

sively through the machine along a path 55 below and at right angles to the path of movement of the magazines. As each magazine is halted in addressing position, inking devices (not shown) act through an operatively positioned stencil to imprint an 60 address thereon. The magazines then move forward and the stencils move transversely to bring a new magazine and a new stencil in co-operative relation.

The mechanism for thus feeding the magazines and stencils and for impressing the 65 address on the magazines forms no part of my present invention and is not shown in detail herein.

My improved route marker device comprises a marking arm 12 (Fig. 2) pivoted at 13 on 70 a fixed bracket 14 and having an upwardly extending arm 15 to which is pivotally connected a solenoid plunger 16. The plunger 16 extends within a solenoid coil 17 having wires 18 and 19 (Fig. 1) connected to its 75 terminals. A spring 20 on the plunger 16 normally holds the marking arm 12 yielding-ly raised above the path of the magazines.

Any suitable marking device may be provided on the arm 12. As shown herein, the 80 marking device comprises a wick or tape 21 having a portion extending through slots 22 in the lower face of the arm 12 and having its remaining portion disposed in a pocket 23 adapted to contain ink or other 85 marking material. Whenever the solenoid is energized, the plunger 16 will be drawn therein and the arm 12 will swing quickly downward, causing the wick or tape 22 to engage a magazine and place a conspicuous 90 mark 24 thereon as shown in Fig. 4.

The wire 18 connects the solenoid to a contact screw 25, mounted on a plate 26. A second contact stud 27 is secured in a pivoted arm 28 and is yieldingly held in 95 engagement with the contact screw 25 by a spring 29. The spring 29 also forms a part of the circuit from the stud 27 through a binding screw 30 and wire 31 to a contact spring 32 engaging a rotary circuit closing 100 member 33. The wire 19 from the solenoid 17 is similarly connected to a second contact spring 34.

The rotary member 33 is of insulating material but is provided with a metal con- 105 ducting plate 35 at one point in its cir-

cumference. The contact springs 32 and 34 are mounted on an insulating base 36 and there is no electrical connection between them except at the instant when they both 5 rest on the plate 35 of the rotating circuit closing member 33.

The arm 28 supporting the contact stud 27 is pivoted at 37 to the plate 26 and is provided with a laterally projecting arm 38 10 which is positioned for engagement by the stencils and which acts as a stencil feeler or detector. The arm 38 preferably has a rounded lower portion 39 which is engaged and raised by a stencil passing thereunder, 15 thus separating the contact points 25 and 27 and preventing the operation of the solenoid when the contact arms 32 and 34 are connected through the plate 35.

At or near the end of each route, a stencil 20 S' has a portion of one corner cut away, as indicated at 40, and the feeler 39 is so positioned that this stencil S' will stop in its intermittent advance with the portion 40 directly under the stencil feeler or detector 38. 25 This permits the detector to swing downward, which in turn permits the contact points 25 and 27 to engage each other and thus complete the electric circuit from the solenoid to the contact arms 32 and 34. The 30 rotating device 33 is so timed in relation to the driving mechanism of the magazine and stencil feeds that the plate 35 will engage and connect the arms 32 and 34 while the stencil S' is in position permitting engagement 35 of the contact points 25 and 27.

The solenoid circuit is thus completed and the marking arm 12 will be actuated to place a mark 24 upon the last magazine of that route. As the magazines are thereafter delivered 40 from the addressing mechanism, the operator need merely separate and assemble the magazines at the different route marks.

The parts are so timed that the plate 35 closes and opens the circuit through the 45 arms 32 and 34, while the contact points 25 and 27 remain in engagement. It is obvious that the rotating member 33 may be placed at any distance from the stencils, magazines and marking mechanism and that it may be 50 suitably enclosed to avoid the possibility of fire which might start from the spark when the circuit is broken. This is an important advantage over certain route markers heretofore used in which the circuit was closed 55 and broken directly by the stencil itself, an arrangement which made it practically impossible to enclose and protect the circuit breaking elements.

Having thus described my invention and 60 the advantages thereof, I do not wish to be limited to the details herein disclosed other-

wise than as set forth in the claims, but what I claim is:—

1. A route marker comprising a marking device, an electrical operating mechanism 65 therefor including a circuit for the operating current, a normally closed contact device in said circuit opened by engagement with a regular stencil and remaining closed during the printing interval on the presentation thereto of a stencil having special provision to indicate the end of a route, a second and normally open contact device in said circuit in series with said first device, and means to close said second contact device 75 during the printing interval.

2. A route marker comprising a marking device, an electrical operating mechanism therefor including a circuit for the operating current, a normally closed contact device in said circuit opened by engagement with a regular stencil and remaining closed during the printing interval on the presentation thereto of a stencil having a portion 80 cut away to indicate the end of the route, a second and normally open contact device in said circuit in series with said first device, and means to close said second contact device 85 during the printing interval.

3. A route marker comprising a marking device and controlling devices therefor, said devices including a regularly operated contact device opened and closed at each addressing operation of the machine and a second contact device normally closed but held open by engagement with a regular stencil at the time when said first contact is closed, said second contact device remaining closed during the printing interval on presentation of a special stencil indicating the 90 end of a route.

4. A route marker comprising a marking device, an electrical operative mechanism therefor, a regularly actuated contact closer, and a second and normally closed contact device opened by engagement with a regular stencil in the machine but remaining closed during the printing interval when a special route-indicating stencil is presented thereto.

5. A route marker comprising a marking device, an electrical operative mechanism therefor, a regularly actuated contact closer, and a second and normally closed contact device opened during the passage of regular stencils through the machine but remaining 105 closed during the printing interval on presentation of a stencil having a portion cut away at its point of engagement with said second contact device.

In testimony whereof I have hereunto 110 affixed my signature.

EDWIN R. SMITH.
